LOAD LIFTER-ACTUATING MEANS

Christian Christiansen, Fargo, N. Dak.

Application May 13, 1936, Serial No. 79,574

6 Claims. (Cl. 214—113)

The invention aims to provide a new and improved means for actuating load lifters, principally of the general type disclosed in my U. S. application Serial No. 56,379, filed December 27, 1935, now Patent No. 2,065,171, dated Dec. 22, 1936, and the present application is a continuation in part of said application.

The load-lifting means is operated by winding a cable on a power driven drum, and an object 10 of the invention is to provide for automatically discontinuing the driving of said drum when said load-lifting means has been lifted to a predetermined extent.

A further object is to provide a novel mechanism including manually actuated control means having a single hand lever which is operative in one manner to either start or discontinue the driving of the drum, and is operative in another manner to apply a brake for checking the descent of the load-lifting means after dumping the load.

With the foregoing in view, the invention resides in the novel subject matter hereinafter described and claimed, the description being accomplished by reference to the accompanying drawings.

Fig. 1 is a perspective view of a load lifter embodying the present invention.

Fig. 2 is an enlarged perspective view.

Fig. 3 is a sectional view substantially on line 3—3 of Fig. 2, the drum-driving clutch being shown in thrown-in or engaged position.

Fig. 4 is a view similar to Fig. 3 but showing the clutch thrown out or disengaged.

Certain specific features of construction have been shown for illustrative purposes and while they will be rather specifically described, it is to be understood that within the scope of the invention as claimed, variations may be made.

The load lifter in connection with which the improved actuating means has been shown, is of the general construction disclosed in the application above mentioned. The base frame 5 is designed to surround a tractor (not shown) and is provided with appropriate hitches 6 for connecting it with said tractor. The frame 5 fixedly carries parallel longitudinal tracks 7 along which slides 8 are movable, said slides being connected with the rear ends of two vertically swingable longitudinal arms 9 whose front ends carry a fork 10 or other load-engaging means. Additional arms 11 are pivoted to the base 5 and to the arms 9, and a block and tackle mechanism is provided for initially angling the arms 9 and 11 when the load-engaging means 10 is in lowered position, and for then moving the slides 8 for-

wardly along the tracks 7, causing lifting of the load. Suitable provision is made to hold the load-engaging means 10 against dumping until desired and I have shown a trip cable or rope 12 for releasing the holding means and allowing 5 load dumping.

Generally speaking, the block and tackle mechanism is the same as that shown in the application above mentioned and it need not, therefore, be described, except to state that it includes an 10 actuating cable or cables 13 which, when wound on a drum 14, cause operation of the load-lifting means, said means being self-lowering when the drive for said drum is discontinued. During raising of the load, the slides 8 move forwardly along 15 the tracks 7 and I utilize this slide movement to operate clutch throw-out means to discontinue driving of the drum 14 when the load-lifting means has been lifted to a predetermined extent, the load being dumped either slightly before or 20 simultaneously with said discontinuing of the drive. I also provide novel control means including a single hand lever which is operable to apply a brake to check the descent of the load-lifting means, said lever being operable in another manner to again throw in or re-engage the drum-driving clutch when the next load is to 25 be lifted, all of which will be hereinafter fully described.

The drum 14 is rotatably mounted in an appropriate supporting structure 15 which preferably includes two spaced vertical plates 16 clamped against opposite edges of the rear base bar 17, by means of bolts or the like 18. The shaft 19 of the drum 14 carries a gear 20 meshing with a pinion 21 on a countershaft 22, which counter-shaft may be mounted in any of the bearing openings 23, as may afford the most convenience in connecting the actuating means with the conventional power take-off shaft of the 40 tractor. The shaft 22 is provided on its front end with a clutch member 24 and with a brake drum 25, said clutch member 24 being co-operable with a shiftable clutch member 26 which is slidable on the rear section 27 of a drive shaft 28. 45 This drive shaft is suitably adapted for connection with the usual power take-off shaft of the tractor and it may, if required, be provided with appropriate universal joints 29. A forwardly and rearwardly shiftable member 30 is operatively 50 connected at its lower end with the clutch member 26, as denoted at 31, the upper end of said shiftable member being preferably provided with a sleeve 32 slidable on a portion of the drum shaft 19. A longitudinal hand lever 33 is ful- 55

crumed at 34 upon the shiftable member 30 and when said lever is pushed rearwardly, it engages the slidable clutch member 26 with the relatively stationary clutch member 24, and disengagement of said member 26 from said member 24 is effected by forwardly pulling said lever 33. The rear end of the lever 33 carries a brake shoe 35 positioned for co-action with the brake drum 25. After the clutch has been thrown out and the load-lifting means starts to descend by gravity, causing retrograde rotation of the drum 14, the rate of descent of said lifting means may be controlled by pulling upwardly upon the lever 33 and causing the brake shoe 35 to exert a proper amount of friction upon the brake drum 25. Suitable releasable locking means 36 may be provided to hold the lever 33 in any desired angular relation with the shiftable member 30.

In addition to the clutch-operating means above described, I provide a transverse clutch throw-out lever 37 which is operatively connected with the slidable clutch member 26, as denoted at 38, said lever being fulcrumed upon any suitable support. In the present disclosure, a bracket arm 39 is bolted to the foremost of the plates 16 and the lever is fulcrumed to this bracket arm. The outer end of the lever 37 is adjustably connected at 40 with an actuating rod 41 which extends longitudinally of one of the tracks 7, said rod having a lateral projection 42 so positioned as to be struck by one of the slides 8 when the load-lifting means has been raised to a predetermined extent. The slide 8 thus forwardly pulls upon the rod 41, actuating the throw-out lever 37 and causing this lever to withdraw the slidable clutch member 26 from the relatively stationary clutch member 24, discontinuing the driving of the drum 14 and allowing the load-lifting means to descend by gravity. During this descent, the lever 33 may be actuated to apply the brake 35 to the drum 25 to control the speed of the winding drum 14 and therefore control the speed at which the load-lifting means may descend. Any suitable guides 43 may be provided for the rod 41, said guides being carried by bracket arms 44 in the present disclosure, which arms are suitably secured to a portion of the base 5.

It will be seen from the above that novel provision has been made for engaging the drum-driving clutch manually, for either automatically or manually disengaging said clutch, and for manually applying a brake to control the speed at which the load-lifting means will descend after the clutch has been thrown out or disengaged.

Should it be necessary to mount the shaft 22 in another position by passing it through certain of the bearing openings 23, the shiftable member 30 may still slide upon the drum shaft 19 and the lever 33 and brake shoe 35 will remain in such position that said shoe may coact with the brake drum 26. It would of course be necessary with such a different positioning of the shaft 22 to change the position of the bracket arm 39. For this purpose, the foremost of the plates 16 is shown as provided with bolt holes 45 to receive the attaching bolt 46 of said bracket arm 39. Shifting of the shaft 22 to another position also necessitates adjustment of the lever 37 with respect to the rod 41, for which purpose the adjustable connection 40 includes a slot 47 or other equivalent means. The connection 40 preferably includes openings 48 in the rear end of the rod 41, and a bolt 49 which may be passed through any of these openings and through the

slot 47. The openings 48 permit longitudinal adjustment of the rod 41 to change the location of the lateral projection 42, so that the desired ascent of the load-lifting means may be permitted before the slide 8 will automatically move the rod 41 to disengage the drum-driving clutch.

From the foregoing and the accompanying drawings, the construction and operation will be understood without further explanation but attention is again invited to the fact that variations may be made within the scope of the invention as claimed.

I claim:

1. In an actuating means for a load lifter having a base and load-lifting means mounted on said base; raising means for said load-lifting means, said raising means including a clutch for stopping the load-lifting operation, and automatic throw-out means for said clutch having an actuator positioned to be actuated by a movable part of said load-lifting means when said load-lifting means has been raised to a predetermined extent, thereby automatically stopping the load-lifting operation.

2. In an actuating means for a load lifter having a base, a longitudinal track thereon, load-lifting means having a slide movable along said track as the load is lifted, and a cable for raising said load-lifting means; a drum for winding said cable, driving means for said drum including a clutch, and automatic throw-out means for said clutch having an actuator mounted adjacent said track in position to be struck and actuated by said slide when the load-lifting means has been raised to a predetermined extent.

3. In an actuating means for a load lifter having a base, a longitudinal track thereon, load-lifting means having a slide movable along said track as the load is lifted, and a cable for raising said load-lifting means; a drum for winding said cable, driving means for said drum including a clutch, a throw-out lever connected with said clutch and disposed at an angle to said track, and a lever-actuating rod connected with said lever and slidably mounted near said track for movement longitudinally of the latter, said rod having a lateral projection positioned to be struck by said slide to actuate said rod and lever and throw the clutch out when said load-lifting means has been raised to a predetermined extent.

4. In an actuating means for a load lifter having a cable-winding drum; drum-driving means having a movable drive-discontinuing member and a brake drum, a movably mounted shifting member operatively connected with said drive-discontinuing member, a lever substantially parallel with the path on which said shifting member is movable, said lever being fulcrumed on said shifting member for use in pushing said shifting member in one direction and pulling it in the other direction by movement of said lever in the direction of its length, one end of said lever being free for manual operation, and a brake shoe cooperable with the aforesaid brake drum and operatively connected with the other end of said lever to be actuated by the latter when the lever is swung about its fulcrum.

5. In an actuating means for a load lifter having a cable-winding drum; a drum-driving shaft having a clutch member and a brake drum, a drive shaft having a slidable clutch member for coaction with the first named clutch member, a movably mounted shifting member operatively connected with said slidable clutch member for moving the latter to and from operative position,

a lever substantially parallel with said shaft and fulcrumed on said shifting member for use in pushing said shifting member in one direction and pulling it in the other direction by movement of said lever in the direction of its length, one end of said lever being disposed at the periphery of said brake drum, and a brake shoe cooperable with the aforesaid brake drum and carried by said one end of said lever to be actuated by the latter when the lever is swing about its fulcrum.

6. In an actuating means for a load lifter having a base frame and a cable-winding drum, said drum having a projecting shaft end; means mounting said drum on said base frame, a counter-shaft geared to said drum shaft, means

mounting said counter-shaft for movement about said drum to any of a plurality of positions, a drive shaft for said counter-shaft, a clutch for connecting said drive shaft with said counter-shaft, a shiftable member connected with said clutch and having a sleeve slidable on said projecting end of said drum shaft, and means for sliding said shiftable member longitudinally of the drum shaft to control said clutch, said sleeve being turnable on the drum shaft according to the position which said shiftable member must occupy when the counter-shaft is moved from one position to another. 5 10 15
